UNITED STATES PATENT OFFICE.

MAXIMILIAN JACKER, OF FLORENCE, WISCONSIN.

WELDLESS-CHAIN MACHINE.

SPECIFICATION forming part of Letters Patent No. 339,781, dated April 13, 1886

Application filed December 13, 1884. Serial No. 150,328. (Model.)

To all whom it may concern:

Be it known that I, MAXIMILIAN JACKER, a citizen of the United States, residing at Florence, in the county of Florence and State of Wisconsin, have invented a new and useful Improvement in Machines for Manufacturing Weldless Chains of Steel, Iron, or other Material, of which the following is a specification.

10 This invention relates to certain improvements in the manufacture of chains; and it has for its object to form the interlocking links from a single bar of metal, as more fully hereinafter specified. This object I attain by 15 the means illustrated in the accompanying drawings, in which—

Figure 1 represents a view, partly in side elevation and partly in section, showing my improved machine complete with the gearing 20 for driving the rolls in unison with each other. Fig. 2 represents a detached view of one of the rolls; Fig. 3, a detached view of a section of the chain; Fig. 4, a side elevation showing a portion of two of the die-rollers employed 25 to form the chain, and Fig. 5 a detached view of one of the die-rollers employed in the formation of the chain.

The letters *a c* indicate a series of four die-rollers, which are set in planes at right angles to each other, and which are mounted upon shafts *f g h k*, journaled in suitable bearings in the frame of the machine. These rollers are beveled at their peripheries, so as to 30 "miter" at their junction, as shown in Fig. 1 35 of the drawings. The peripheries of the rollers at their adjoining beveled edges have formed in them semicircular recesses or matrices *m*, which act as dies in the formation of the chain, as more fully hereinafter specified.

40 The shafts *f g h k p r s* and the cog-wheels and pinions *t u* connect with the main driving-shaft *v* by means of intergearing wheels, by which they are all driven in unison, so as to

bring the dies together in proper relative positions to swage the links of the chain. 45

The operation of my invention is as follows: The parts being arranged as described, a rotary movement is imparted to the rollers by power applied to the shaft *f*. The blank, which is of suitable size, is fed in between the 50 rollers at the front of the machine, and is carried forward between them automatically. In passing between the rollers the dies on their beveled peripheries partially press or swage out the links alternately at right angles to each other, leaving the pressed blank after passing between them in such shape that the links may be easily separated from the weak connecting parts by tumbling the blanks in a rotating cylinder, which, besides breaking 55 the connecting webs, will finish the connecting-links of the chain and polish the same, as metallic shot and other articles are finished and polished.

It will be seen that the links as thus formed 60 will be all integral or a part of the original blank, and will require no welding, while the facility and rapidity with which the chain may be made will materially reduce the cost of manufacture. 70

Having thus described my invention, what I claim is—

The combination of the beveled rollers arranged to miter at their junction and provided with a series of curved matrices at their 75 peripheries, the ends of the matrices on one of the rollers being opposite the centers of the matrices on the opposite roller, the rollers being arranged so that the matrices will retain these relative positions as the rolls are 80 rotated, substantially as specified.

MAXIMILIAN JACKER.
